US00D782108S

(12) **United States Design Patent** (10) **Patent No.:** **US D782,108 S**
Jordan et al. (45) **Date of Patent:** ** *Mar. 21, 2017

(54) **MOUTHPIECE FOR ELECTRONIC VAPING DEVICE**

(71) Applicant: **Altria Client Services LLC**, Richmond, VA (US)

(72) Inventors: **Geoffrey B. Jordan**, Midlothian, VA (US); **Charles Dendy**, Richmond, VA (US); **Bipin Patil**, Richmond, VA (US)

(73) Assignee: **Altria Client Services LLC**, Richmond, VA (US)

(*) Notice: This patent is subject to a terminal disclaimer.

(**) Term: **15 Years**

(21) Appl. No.: **29/527,153**

(22) Filed: **May 15, 2015**

(51) **LOC (10) Cl. 27-02**

(52) **U.S. Cl.**

USPC **D27/167**; D27/170

(57) **CLAIM**

The ornamental design for a mouthpiece for electronic vaping device, as shown and described.

DESCRIPTION

FIG. 1 is a first perspective view of the mouthpiece for electronic vaping device;

FIG. 2 is a second perspective view of the mouthpiece for electronic vaping device;

FIG. 3 is a front view of the mouthpiece for electronic vaping device;

FIG. 4 is a side view of the mouthpiece for electronic vaping device; and,

FIG. 5 is a bottom view of the mouthpiece for electronic vaping device.

In the drawings, the broken lines depict environmental subject matter only and form no part of the claimed design.

1 Claim, 3 Drawing Sheets
